UNITED STATES PATENT OFFICE.

JOHN LAYNG McKIM, OF LONDON, AND JOHN JOHNSTON, OF WESTMINSTER, LONDON, ENGLAND; SAID JOHNSTON ASSIGNOR TO SAID McKIM.

PNEUMATIC APPARATUS FOR APPLYING ROUGH-CAST OR OTHER PLASTER TO THE WALLS OF BUILDINGS OR STRUCTURES OR OTHER SURFACES.

1,239,283.

Specification of Letters Patent.

Patented Sept. 4, 1917.

Application filed March 31, 1917. Serial No. 159,022.

To all whom it may concern:

Be it known that we, JOHN LAYNG Mc-KIM and JOHN JOHNSTON, both subjects of the King of Great Britain, residing, respectively, at 22 Great St. Helens, London, England, and The Globe Pneumatic Engineering Co., Ltd., 1 Victoria street, Westminster, London, England, have invented new and useful Improvements in Pneumatic Apparatus for Applying Rough-Cast or other Plaster to the walls of Buildings or Structures or other Surfaces, of which the following is a specification.

This invention relates to apparatus for applying an aggregate of sand, granite or other chips or the like, mixed with lime or cement in the form of plaster to walls, or to the surface of girders or other structures, and to that class of such apparatus wherein air pressure is employed for expelling the plaster from a nozzle to which it is conveyed.

According to the present invention use is made of a vacuum in conjunction with air pressure, the vacuum being used for conveying the plaster materials to the point at which, or adjacent to that at which, they are acted upon by the air pressure for carrying them into contact with the water and applying them to the surface to be coated.

In carrying out the invention there is provided what may be termed a centrifugal chamber and a collector chamber, the former of which is connected to an apparatus for exhausting the air therefrom and is also provided with a nozzle for the connection of a pipe through which the component parts of the plaster are to be drawn by means of the vacuum, the said nozzle being advantageously arranged tangentially in order that the components, which are in a dry condition, will enter with a whirling motion. The collector chamber is in open communication with the centrifugal chamber and has connected to it a hollow cone or sleeve through which the components are delivered into a compressed air nozzle surrounding the said cone, the said compressed air nozzle having

combined with it means for ejecting a spray of water through which the materials will be forced by the air pressure.

The invention will be readily understood by reference to the accompanying drawings, in which:—

Figure 1 is a sectional side view of our improved apparatus, and

Fig. 2 is a sectional plan.

Fig. 3 is a section on the line 3—3, Fig. 1. *a* indicates the centrifugal chamber, which is preferably of cylindrical form and has a pipe *b* arranged axially within it, one end of which is in open communication with the interior of the said chamber, while the other end is designed to be connected to a pump or exhauster by means of which a partial vacuum can be maintained in the said centrifugal chamber. Externally the centrifugal chamber has applied to it a tangential nozzle *c* to which a conductor pipe can be connected and through which the component parts of the plaster are designed to be drawn by means of the vacuum produced in the said centrifugal chamber, the tangential arrangement being employed in order that the said components, which are in a dry condition, will enter with a whirling motion and become thoroughly intermingled.

d is the collector chamber which is applied upon the wall of the centrifugal chamber and is connected to the latter by a slot or opening *e* in such a manner that as the materials are caused to whirl in the centrifugal chamber *a* they will gradually gravitate through the said opening *e* into the said collector chamber.

f is the hollow cone or sleeve through which the material collecting in the chamber *d* is discharged, the said cone or sleeve being inclosed by a hollow casing *g* in such a manner that an annular opening *h* is formed around the mouth of the said cone or sleeve *f*, the said opening *h* being in communication with a pipe *i* through which compressed air can be supplied.

The casing *g* is extended in front of the cone or sleeve *f*, to form a nozzle *k* through

which the materials are discharged under the pressure of the air issuing through the annular opening *h*, and this nozzle *k* is surrounded by a water nozzle *l* formed by two sleeves *m*, *m*¹ adjustably fixed upon the nozzle *k* and having their outer ends brought into coincidence in such a manner that an annular passage can be formed between them through which water will be sprayed 10 on to the dry material discharged through the nozzle *k*. Water is supplied to the nozzle *l*, by pipes connected to the sockets *n*, through the passages *o*, *o* and the space *p* between the two sleeves *m*, *m*¹.

15 With this arrangement hereinbefore described it will be understood that when air, at sufficient pressure, is discharged through the annular opening *h* a vacuum will be produced in the cone or sleeve *f* and will draw 20 the material deposited in the collector chamber *d* into the nozzle *k* and discharge it. As, however, the chamber *d* and the centrifugal chamber *a* are under a partial vacuum, produced by the exhauster, as before described, 25 the velocity of the air issuing through the annular opening *h* must be sufficient to counteract the action of the vacuum which tends to draw the material back out of the cone or sleeve *f* into the collector chamber.

30 As the material is driven by the air through the nozzle *k* water is caused to issue through the annular opening in the water nozzle *l* in sufficient quantity to wet the dry material to the requisite extent for causing it to 35 adhere to the surface to be covered.

q, *q*¹ are handles which are connected to the centrifugal chamber and which serve for manipulating the apparatus.

In the apparatus shown, the delivery nozzle is applied directly to the collector chamber. If desired, however, the various nozzles and the means for supplying water or compressed air to the latter may be made independent of the said collector chamber 45 and connected to the latter by a flexible pipe or hose; this arrangement has the advantage that the nozzles can be handled with much greater facility than when combined with the centrifugal and collector chambers, and 50 when the nozzles are thus separately formed, the collector and centrifugal chambers may be mounted upon a stand.

In order that the operator may control the discharge, the pipe *b*, through which the centrifugal chamber is exhausted has 55 arranged in conjunction with it a valve *r* the opening of which serves to admit air into the centrifugal chamber and so prevent the material from being drawn into the latter under the action of the suction. As shown in Fig. 2, this valve is arranged in conjunction with a lever *s* connected to a rod *t* in a position adjacent to one of the handles *q* so as to be easily operated by a finger. 60

65 *u* indicates a filter of wire gauze or the

like, which is placed around openings in the pipe *b*, for preventing the sand and other materials from being drawn into the exhauster. *v*, *w* are rubber linings arranged in the cone *f* and the nozzle *k* respectively 70 and which can be renewed from time to time as they become worn by the material which passes through them.

Having now particularly described and ascertained the nature of our said invention and in what manner the same is to be performed, we declare that what we claim is:

1. In an apparatus for applying rough cast or other plaster to walls or the like, a 80 cylindrical mixing chamber, a tangential inlet passage for conveying material to said chamber, and a passage for exhausting air from said chamber, whereby the material is drawn into the chamber and whirled about 85 the same to mix said material.

2. In an apparatus for applying rough cast or other plaster to walls or the like, a cylindrical mixing chamber, a collector chamber into which the material passes 90 from the mixing chamber after the same has been mixed, a tangential inlet passage for conveying the material to said mixing chamber, and a passage for exhausting air from said mixing chamber, whereby the material is drawn into the mixing chamber and whirled about the same to mix said material. 95

3. In an apparatus for applying rough cast or other plaster to walls or the like, a 100 cylindrical mixing chamber provided with an outlet slot, a tube arranged axially within said chamber and provided at its forward end with apertures through which air may be exhausted from said chamber, a tangential nozzle connected to the wall of the mixing chamber near the rear end of the same for admitting the material to said chamber, and a collector chamber connected to the mixing chamber for catching the 110 material which falls through said slot. 105

4. In apparatus for supplying rough cast or other plaster, a cylindrical mixing chamber provided with an outlet slot, a tube arranged axially within said chamber and provided at its forward portion with apertures through which air may be exhausted from said chamber, a valve for normally preventing exterior air from entering said pipe, a tangential nozzle connected to the 120 wall of the mixing chamber near the rear end of the same, for admitting plastering material to said chamber, and a collector chamber for catching the material which falls through said slot. 115

5. In an apparatus for applying rough cast or other plaster, a chamber into which the plaster materials are drawn under the action of a vacuum produced in said chamber, a second chamber connected thereto in 125 130

which the materials drawn into the other chamber collect, and a nozzle through which said collected materials are discharged.

6. In an apparatus for applying coating
5 to walls or the like, the combination of a chamber into which the plaster materials are drawn under the action of a vacuum produced in the said chamber, a second chamber connected thereto into which the
10 materials drawn into the other chamber collect, a nozzle through which such collected materials are discharged, means for producing a current of air around the said

nozzle and means for wetting the materials as they are discharged against the surface to 15 be coated, substantially as described.
